CLAIM

The ornamental design for a tier apron with fold pockets, as shown and described.

DESCRIPTION

FIG. 1 is a front right perspective view of a tier apron with fold pockets showing my new design, the left perspective view being a mirror image;

FIG. 2 is a front elevational view thereof; and,

FIG. 3 is a rear elevational view thereof.

The broken lines shown in the Figures including the mannequin, the top and bottom of the apron as well as conventional stitching on an apron with tier fold pockets illustrate the environment only and form no part of the claimed design.
